ARTICLE CARRYING DEVICE

Paul Beckwith, Stroudsburg, Pa.

Application August 3, 1937, Serial No. 157,079

2 Claims. (CL. 224—26)

This invention relates to article carrying devices and comprehends a carrier for articles such as cigarettes whereby the same may be directly supported from the leg or arm of the wearer.

5 Broadly the invention comprehends an article carrier which includes a limb encircling band and cooperative means associated therewith to support a limited supply of cigarettes or analogous articles whereby the same may be separately withdrawn without affecting the support of those remaining in the carrier.

10 More particularly the invention is directed to a cigarette carrier embodying an elastic band adapted to surround the limb of the wearer and contractively retained in place thereon with a rigid element associated therewith which is so constructed and arranged as to dispose a length of the elastic band in a spanning relation and parallel to a portion thereof so as to clamp the articles therebetween and to space the same from the limb of the wearer.

15 Other objects of the invention reside in the provision of a device of the indicated character which is extremely simple in its construction and mode of use, and which is highly efficient for its intended purpose.

20 With the above enumerated and other objects in view, reference is now made to the following specification and accompanying drawing in which there is disclosed, by way of example, a preferred embodiment of the invention, while the appended claims cover variations and modifications falling within the scope of the invention.

25 In the drawing:

Fig. 1 is a perspective view of the cigarette carrier in applied position on the leg of the wearer.

30 Fig. 2 is a fragmentary perspective view on a larger scale as viewed from the inner side of the device.

35 Fig. 3 is a horizontal sectional view taken approximately on the line 3—3 of Fig. 2.

Referring to the drawing by characters of reference, 10 designates an elastic band which is of a size to contractively fit around the leg or arm of the wearer and which may be provided with clasp means 11 for connecting the ends thereof to facilitate the application to and removal of the same from the limb of the wearer.

40 The device also includes a rigid substantially U-shaped element 12 which may be constructed from sheet metal, Celluloid or any equivalent material and which element consists of a bridge or bight portion 13 having angularly disposed leg

portions 14 at the opposite ends which taper towards the free terminals thereof and are formed with outwardly directed angularly disposed feet 15.

5 The leg portions 14 are provided with parallel transverse slots 16 and 17 through which the elastic band 10 is trained so that the length thereof, indicated at A, is disposed in spanning relation to the legs 14 and is arranged parallel to and normally spaced from the bridge or bight portion 13 a distance less than the diameter of the articles or cigarettes B as indicated in broken lines in Fig. 3. It will be understood that the spanning length A is stretched and placed under tension when the cigarettes or articles B are inserted as shown in full lines in Fig. 3 so as to clamp and retain said articles between said length A and the bridge or bight portion 13. It will also be apparent that the removal of one or more of the articles B from their clamped 15 position between the length A and bight portion 13 will not affect the retention of those remaining in the carrier as the elasticity of the spanning length A is sufficient to retain one or more articles in position.

20 It will also be observed that the elastic band 10 is trained around and under the terminal portions or feet 15 of the legs 14 so as to avoid contact of the element 12 with the skin of the limb C while the legs are of a sufficient length to 30 space the articles B and the spanning length A from the surface of the limb C. The terminals or feet 15 provide adequate bearing surfaces to insure the stable support of the article on the limb and to avoid any discomfort to the wearer.

35 The device is ideally adapted for use in carrying a limited supply of cigarettes on the person of the wearer when in a bathing suit, on the beach or on other occasions.

40 What is claimed is:

1. An article carrier including an elastic band adapted to surround the limb of the wearer, and a rigid U-shaped element comprising a bridge portion and angularly disposed leg portions extending from said bridge portion towards the 45 limb, each leg portion having a pair of parallel slots spaced from the bridge portion and said band extending through the slots adjacent the bridge portion to dispose a length thereof in spanning relation to the leg portions and parallel to the bridge portion to clamp the articles between said band and bridge portion with the opposite ends of the band extending respectively through the remaining slots and outwardly around the free ends of the leg portions respec- 50 55

tively to space the bridge portion and the said spanning length of the band from the limb of the wearer.

2. An article carrier including an elastic band
5 adapted to surround the limb of the wearer, a
rigid U-shaped element comprising a bridge portion
having angularly disposed leg portions ex-
tending inwardly from the bridge portion to-
wards the limb and disposed in endwise relation
10 therewith, means disposed transversely of and
intermediate the length of each leg portion

around which means the band extends to dis-
pose a length thereof in spanning relation to the
leg portions and spaced from the limb of the
wearer and parallel to the bridge portion for
clamping articles between said spanning por-
tion of the band and the bridge portion with
the opposite ends of the band extending out-
wardly around the inner ends of the leg portions
respectively and between the inner ends thereof
and the limb. 10
